UNITED STATES PATENT OFFICE.

PERCIVAL B. FRENCH, OF CHICAGO, ILLINOIS.

CLEANING ATTACHMENT FOR PLAYER INSTRUMENTS.

1,145,009.

Specification of Letters Patent.

Patented July 6, 1915.

Application filed May 20, 1914. Serial No. 839,667.

To all whom it may concern:

Be it known that I, PERCIVAL B. FRENCH, a citizen of the United States, and a resident of Chicago, in the county of Cook and State 5 of Illinois, have invented certain new and useful Improvements in Cleaning Attachments for Player Instruments, of which the following is a specification.

My invention relates to improved cleaning 10 attachment for player instruments, such as player pianos, organs or the like.

In such player instruments suction is depended upon as a motive force for the various playing and regulating pneumatics, the 15 flow of air being controlled by the passage of a perforated music sheet over a tracker board, in the well known manner. The air rushing into the tracker board and through the various ducts, compartments, and pneumatic 20 devices when the music sheet perforations register with the tracker board openings, carries with it dust, dirt and lint from the music sheet and such dust and lint will eventually tend to clog up the passageways 25 and vent openings. Crude methods and apparatus have been used for cleaning out the pneumatic systems, ordinary suction hand 30 pumps provided with a tool having been resorted to, the tool being applied to the tracker board openings while the pump was operated, the intention having been to draw the dust out of the system back through the 35 tracker board openings.

The important object of my invention is 40 therefore to provide an efficient cleaning attachment permanently associated with the instrument and the player mechanism therein and for such cleaning attachment I preferably utilize the pedal or power controlled feeder bellows or power suction motor for providing efficient suction. As such feeder bellows or power suction motor are also connected with a pneumatic motor for driving the spools controlling the passage of the 45 music sheet over the tracker board, and as it is desirable to disconnect the motor during cleaning operations, another object of my invention is to provide valve mechanism for automatically disconnecting the motor 50 when the cleaning attachment is utilized.

Another object of the invention is to simplify the use of the cleaning mechanism in order that any person can readily and efficiently use the same, and for this purpose 55 I provide improved and simplified valve mechanism which is normally set so as not

to interfere with the ordinary playing operation of the instrument, but which is automatically set, by the mere insertion of a plug, to effect control of the automatic valve 60 mechanism to disconnect the motor and to connect the suction source directly with the inserted plug and with a tube extending therefrom and terminating in a cleaning tool which can be passed back and forth over 65 the tracker board openings to thus effect cleaning of the system.

The various features of the invention are clearly illustrated on the accompanying sheet of drawings in which—

Figure 1 is a diagrammatic lay out of the well known player mechanism parts, and my improved cleaning attachment applied thereto, Fig. 2 is an enlarged front elevational view of the plug controlled valve 75 mechanism, Fig. 3 is a sectional view on plane 3—3, Fig. 2, Fig. 4 is a side elevational view of the plug controlled mechanism, when the valve mechanism is in normal position, and Fig. 5 is an enlarged sectional view on plane 5—5, Fig. 4, showing the plug inserted and the valve mechanism 80 set for cleaning operation.

Referring to Fig. 1, B diagrammatically represents bellows which may be driven by 85 foot or by a motor or which could be an electrically driven suction device. A diagrammatically represents the action including the key actuating pneumatics, regulating pneumatics, etc., this action being connected by a duct *a* with the suction feeder *B*. C represents the spool box in which the tracker board *T* is arranged between the winding and re-winding spools *S* and *S'*, respectively. M represents the motor for 95 controlling the operation of the spools and the passage of a music sheet over the tracker board whose openings *o* are connected by ducts *d* with the key controlling pneumatics of the action *A*.

The invention contemplates the provision of a plug barrel 10 adapted for connection with the suction feeders and adapted to receive a plug 11 with which a cleaning tool *t* is connected by a flexible conductor 12, the 105 tool being passed back and forth over the tracker board to communicate with the openings *o* therein in order to withdraw the dust and dirt from the system. Ordinarily the motor *M* would be connected directly with 110 the suction source *B* but in order to disconnect the motor during cleaning operations

so that the entire suction can be utilized for cleaning, I provide a valve structure V. As shown, this structure comprises a tube 13 closed at its upper and lower ends by caps 5 14 and 15, respectively, and having an inner partition 16 to form upper and lower chambers 17 and 18. The suction source B is connected with the chamber 18 by a duct b, the chamber 17 being connected by duct c with 10 the motor M. An inner tube 19 is supported by the partition 16 and serves under certain conditions to afford communication between chambers 17 and 18. However, the cap 14 supports a diaphragm 20 carrying the valve 15 21 which under certain conditions is adapted to close the upper outlet of the tube 19 to thus disconnect the chambers 17 and 18, a spring 22 tending to hold the valve away from the tube. In order to control the operation 20 of the automatic valve V valve mechanism v is provided in the plug barrel 10 to be controlled by the plug 11. Extending from and communicating with the plug barrel 10 is a nipple 23 which is connected by a conductor 24 with the compartment 18 of the automatic valve V. The valve sleeve 25 is reciprocable within the plug barrel and its inner end has the tongue 26 which extends through the slot 27 in the barrel 10, a 25 spring 28 connecting between the tongue and the escutcheon plate 29 from which barrel 10 extends, tending to hold the valve sleeve forwardly in the barrel and in position to be engaged by the tubular plug 11 to be 30 shifted rearwardly when the plug is inserted in the barrel 10. The valve sleeve 25 has the partition 30 which with the closed end 31 of the sleeve forms the valve chamber 32, a nipple 33 extending from the end wall 31 35 being connected by conductor 34 with the diaphragm chamber 35 formed between the cap 14 and the diaphragm 20 in the valve V. The valve chamber 32 has the port 36 adapted to communicate with the nipple 23 when 40 the valve sleeve is in forward position as indicated in Figs. 1 to 4, such port leaving the nipple 23 and coming into register with the atmosphere port 37 when the valve sleeve has 45 been shifted rearwardly by the plug 11, Fig. 5. The front valve chamber 38 with which the inserted plug connects has a port 39 which is closed by the barrel 10 when the plug is withdrawn but which registers with the suction inlet nipple 23 when the plug is inserted, Fig. 5.

In order to lock the plug in the barrel against the force of spring 28, a bayonet lock is preferably provided, the plug having the pin 40 extending therefrom and the 60 barrel 10 having the bayonet slot 41, the plate 39 being slotted at 42 to allow passage of the pin 40 therethrough. The tool t shown comprises a plate 43 from which the fitting 44 extends, the plate 43 supporting 65 a block 45 preferably faced with leather 46.

From the above description the operation is apparent. Under normal conditions the valve sleeve 25 is held forward by the spring 28 and conductors 24 and 34 are in communication through port 36 and chamber 32. 70 The chamber 18 and the diaphragm chamber 35 of the automatic valve V are then both connected with the suction source B and the pressure is equal at the opposite sides of the diaphragm 20, valve 21 being 75 therefore held above the tube 19 by the spring 22. Chamber 17 is also connected with the suction source and the motor M is connected for service. When the plug is inserted (Fig. 5) port 36 is disconnected 80 from conductor 24 and when the port registers with the atmosphere port 37, the valve chamber 32 and the diaphragm chamber 35 will be under atmosphere pressure. Chamber 18 and the interior tube 19 being still 85 under vacuum, the diaphragm 20 will be actuated and valve 21 caused to close the tube 19 to thereby disconnect the chamber 17 from the suction source and to disconnect the motor M. The suction source B is then 90 connected only with the valve chamber 38 through port 39 and with the tool t connected with the plug. The tool is then shifted back and forth over the tracker board and the dust, lint and other accumulation will 95 be sucked into the device B. Thus by merely inserting the plug in an opening a cleaning tool is connected with the suction source and the entire suction is available for the cleaning tool and very rapid and efficient cleaning 100 can be accomplished. It is unnecessary to actuate any valves, levers, or the like as the motor is cut out entirely automatically when the plug is inserted. When the plug is withdrawn normal conditions are restored and 105 the motor is again operative.

In Fig. 1 I have shown the escutcheon plate 29 of the plug valve mechanism secured to the upper wall e of the spool box C, while in Fig. 2 the escutcheon plate is 110 shown secured in vertical position to the spool box. It is evident, of course, that the plate could be applied in other positions in order that the plug can be accurately and conveniently inserted. It is also evident 115 that different kinds of cleaning tools could be connected with the plug and utilized for cleaning other parts of the instrument, as for example the key-board, to draw out the dust which is apt to accumulate on and between the keys.

I do not desire to be limited to the exact constructions and arrangements shown, and I claim the following:

1. In combination with a player instrument comprising a suction producing device and a pneumatic device normally connected therewith, of a cleaning attachment, means for connecting such cleaning attachment with the suction producing device, and 125 130

means for automatically disconnecting said pneumatic device from the suction producing device upon connection of said cleaning device therewith.

- 5 2. In combination with a player instrument comprising a suction producing device and a pneumatic device normally connected therewith, of a pneumatic cleaning attachment, means for connecting said cleaning attachment with the suction producing device, and valve mechanism for automatically disconnecting said pneumatic device from said suction producing device upon connection of the cleaning attachment with the suction producing device.

- 10 3. The combination with a suction player instrument comprising a suction producing device and a pneumatic device normally connected therewith, of a pneumatic cleaning tool normally disconnected from said suction producing device and means for connecting it therewith, and means automatically controlled by the connection of said tool with the suction producing device for disconnecting said pneumatic device from said suction producing device.

- 15 4. In combination with a player instrument comprising a suction producing device and a normally operative pneumatic device, of a cleaning attachment normally disconnected from said suction producing device, a valve for controlling the connection of said attachment with the suction producing device, and means controlled by the operation of said valve for automatically rendering said pneumatic device inoperative.

- 20 5. In combination with a player instrument comprising a suction producing device and player mechanism adapted to be driven thereby, of a pneumatic cleaning conductor connected with said suction producing device, a plug adapted for insertion in said conductor and a cleaning tool connected with said plug, and valve mechanism actuated by the insertion of the plug to connect the tool with the cleaning conductor.

- 25 6. In combination with a suction player instrument comprising a suction producing device and a pneumatic device to be operated thereby, of a conductor leading from said suction producing device, a cleaning tool and means for connecting it with the inlet of said conductor, a controlling valve interposed in said conductor and normally closing the inlet thereof, an automatic valve structure connected with said suction producing device and with said pneumatic device, an atmosphere connection with said automatic valve controlled by said controlling valve and normally closed thereby, said automatic valve during closure of said at-

mosphere connection being controlled by suction to effect communication between the suction producing device and said pneumatic device, and means controlled by the connection of said tool with said conductor to shift said controlling valve to open the conductor inlet to the tool and to open the atmosphere connection, and means whereby opening of the atmosphere connection will effect disconnection of the pneumatic device from the suction producing device.

7. A pneumatic cleaning attachment for suction player instruments comprising a valve structure, a conductor leading from said valve structure for connecting said structure with the instrument suction producing device, the valve of said structure being normally closed, a cleaning tool and means for connecting it with said valve structure, and means controlled by the connection of the tool with the structure for effecting opening of the valve.

8. A cleaner attachment for player instruments having a suction producing element comprising a plug barrel, a valve within said barrel, a conductor leading from said plug barrel to the suction producing element, said valve normally closing the inlet to said conductor, a plug adapted to be inserted in said barrel to coöperate with the valve to effect opening of the conductor inlet, and a cleaning tool connected with said plug.

9. In a suction player instrument, the combination of a suction producing device, a pneumatic device, a main valve structure normally connecting the pneumatic device with the suction producing device, a conductor leading from said suction producing device, a cleaning tool and connecting means for connecting it with said conductor, a controlling valve interposed in the path of connection of said connecting means with said conductor, said valve being normally in position to close the conductor and shifted upon connection of the connecting means with the conductor to connect the conductor with the connecting means and tool, and pressure controlling means for said main valve controlled upon shifting of the controlling valve to change the pressure conditions of the main valve to effect disconnection thereby of the pneumatic device from the suction producing device.

In witness whereof, I hereunto subscribe my name this 9th day of May, A. D., 1914.
